TELEPHONE MEMORANDUM BRACKET

James B. O'Donnell, Jr., Mount Washington, Ohio

Application March 31, 1950, Serial No. 8,895

Term of patent 14 years

(Cl. D74—1)

To all whom it may concern:

Be it known that I, James B. O'Donnell, Jr., a citizen of the United States, residing at Mount Washington, in the county of Hamilton and State of Ohio, have invented a new, original, and ornamental Design for a Telephone Memorandum Bracket, of which the following is a specification, reference being had to the accompanying drawings, forming a part thereof.

I claim:

The ornamental design for a telephone memorandum bracket, substantially as shown.

JAMES B. O'DONNELL, JR.
